ENGINE STARTER

Samuel Gilbert, Cedar Grove, N. J., assignor to
 Bendix Aviation Corporation, Teterboro, N. J.,
 a corporation of Delaware

Application November 2, 1951, Serial No. 254,542

2 Claims. (Cl. 74—7)

1

The present invention relates to engine starters and particularly to engine starter meshing mechanism.

In engine starters usually some means are required for engaging the starter jaw with the engine to be started. One method used is to frictionally hold the starter jaws to cause axial movement thereof. This method has numerous disadvantages in that the friction means are present during the operation of the starter. Also for starts at low temperatures, the friction means are not adequate for holding the starter jaw to cause the necessary axial movement for jaw engagement.

The present invention provides a clutch between the starter jaw and housing with means responsive to axial movement of the starter jaw to actuate the clutch to a disengaged position. Thus, the starter jaw is restrained from rotation until it has been actuated axially for a predetermined distance.

It is an object of the present invention to provide improved meshing mechanism for an engine starter.

Another object of the invention is to provide an improved starter.

Another object of the invention is to provide improved meshing means for operation at low temperatures.

Another object of the invention is to provide positive meshing means for a starter.

The above and other objects and features of the invention will appear more fully hereinafter from a consideration of the following description taken in connection with the accompanying drawings wherein two embodiments of the invention are illustrated by way of example.

In the drawing:

Figure 1 is a sectional view of an engine starter embodying one form of the invention.

Figure 2 is a perspective view of the starter jaw of Figure 1.

Figure 3 is a section of an engine starter illustrating another embodiment of the invention.

Referring now to Figure 1, the device therein shown comprises a starter assembly including, in general, a motor 1 having a driving shaft 2 rotatably supported by a bearing 3 mounted in end wall 4 of motor housing 5. A pinion 6, shown as integral with the shaft 2 meshes with planet gears

7. The planet gears 7 are rotatably supported by ball bearings 8 mounted on stub shafts 9 carried by spider cage 10. The planet gears 7 mesh with a ring gear 11 securely fastened against rotation by screws 12 to gear housing 13. It is understood,

2

however, that the ring gear 11 may be made integral with the housing 13. The gear housing 13 is secured to the motor housing 5 by screws 14 as shown or by other suitable means.

Integral with the spider cage 10 is a pinion gear 15 adapted to engage planet gears 16 which in turn engage the ring gear 11. The gears 16 are supported by bearings 17 mounted on stub shafts 18 carried by a drum member 19. The drum member or barrel 19 is rotatably mounted in the housing 13 by bearing 20.

The barrel 19 is connected for the transmission of rotary motion to axially stationary spline nut 21 through a torque limiting disc pack 22. The disc pack 22 comprises a plurality of friction discs alternately splined to the inner face of the barrel 19 and the outer face of the spline nut 21. The discs of the pack 22 are forced into frictional engagement with each other by a plurality of circumferentially spaced springs 23 compressed between a flange 24 on the spline nut 21 and an adjustable nut 25 threaded into the barrel 19 and set so that the disc pack 22 will slip at a predetermined torque.

Long lead internal threads 26 of the spline nut 21 mesh with mating threads 27 of screw shaft 28 which is connected to starter jaw 29 by axial splines 30 for rotation therewith. A mesh rod 31 holds the starter jaw 29 into operative relationship with the screw shaft 28. A spring 32 coacts with the mesh rod 31 and screw shaft 28 to effect engagement of the jaw 29 with engine jaw 33 upon axial movement of the screw shaft 28. Also, the spring 32 permits ratcheting upon the engine jaw 33 overrunning the starter jaw 29.

A novel feature of the invention resides in the manner of obtaining and releasing friction for meshing the jaws 29 and 33. The jaw 29 has a circumferential flange 34 and axial splines 35 (see Figure 2). Disc 36 splined to baffle plate 37 coact with the flange 34 to form an interleaved brake 38. The flange 34 and disc 36 are forced into engagement by helical springs 39 compressed between a plate 40 and a spring retaining ring 41. The retaining ring 41 is held on the jaw 29 by a split ring 42 fitted in a groove 43 in the splines 35. The spring 39 forces the disc 36 against the flange 34 for frictional engagement with each other.

A sleeve member 44 surrounds the jaw 29 and has fingers 45 extending through openings 46 in the flange 34 between the splines 35. The outer face of the sleeve 44 has a contour substantially similar to that of the jaw 29. A retaining ring

47 holds the sleeve 44 in operative relationship with the jaw 29.

Oil sealing means are provided by an oil seal ring 48 carried by a baffle wall 49. The wall 49 is secured between the housing 13 and baffle plate 31. The oil seal ring 48 coacts with the spline nut 21 to provide a seal at one end thereof and an O-ring 50 compressed by a split ring 51 provides a seal at the other end.

In operation, upon the motor 1 being energized, the jaw 29 is held against rotation by the brake 38 thereby causing axial movement of the jaw 29. Upon the sleeve 44 abutting the engine jaw 33, the fingers 45 force the plate 40 against the spring 39 thereby removing the pressure of the spring from the disc 36. This removes the friction from the brake with consequent elimination of drag during the starting operation.

Referring now to Figure 3 for another embodiment of the invention wherein only that portion of a starter differing from that shown in Figure 1 is illustrated. It will be apparent how Figure 1 could be modified with the embodiment of Figure 3.

The long lead internal threads of the spline nut 21 mesh with mating threads of screw shaft 55 which is connected to starter jaw 56 by splines 57 for rotation therewith. The jaw 56 is retained in operative engagement by a mesh rod 58 secured to the jaw 56 by a retaining ring 59. A spring 32 coacts between the mesh rod 58 and the screw shaft 55 to effect engagement of the jaw 56.

The screw shaft 55 is connected to baffle plate 60 by an interleaved brake 61 having disc 62 splined to the screw shaft 55 and disc 63 splined to the baffle plate 60. A flange 64 on the baffle plate 60 forms a backing plate for the clutch 61. The discs 62 and 63 are forced into frictional engagement by helical springs 65 compressed between the disc pack 61 and a spring retaining ring 66. A locking ring 67 retains the ring 66 in operative relationship with the springs 65.

The retaining ring 66 comprises ring members 68 and 69 having corresponding ramps 70 and 71. A ball 72 coacts with the ramps 70 and 71 to force the members 68 and 69 apart thus compressing the springs 65.

In operation, the screw shaft 55 is held by the brake 61 against rotation thereby causing it to be moved axially towards an engine engaging position. After the shaft 55 has moved axially a predetermined distance, the ball 72 will drop in groove 73 thus permitting the member 68 to move towards the member 69 to remove the compression from the springs 65. Upon the compression

being removed from the springs 65, the discs 62 and 63 are free to rotate relative to each other and the screw shaft is free to rotate to start the engine. Should the jaw 56 abut before full engagement, the spring 32 is compressed by the mesh rod 58 permitting the screw shaft 68 to travel axially until the ball 72 drops in the groove 73 to remove the pressure on the brake 61.

Upon the engine starting, the jaw 56 is forced back against the springs 32 which will exert a pressure on the screw shaft sufficient to pull the ball 72 out of the slot 73 and thereby force the members 68 and 69 apart.

Although only two embodiments of the invention have been illustrated and described, various changes in the form and relative arrangement of the parts, which will now appear to those skilled in the art, may be made without departing from the scope of the invention.

What is claimed is:

1. In an engine starter the combination of an assembly comprising an axially stationary rotatable spline nut, a screw shaft in said nut, a starter jaw member adapted for rotation with and axial movement relative to said screw shaft, a jaw retaining member, spring means interposed between said jaw retaining member and said screw shaft for urging said jaw member into engagement with an engine jaw upon axial movement of said screw shaft, means including a spring biased disc for preventing rotation of said jaw member to effect axial movement of said screw shaft, a sleeve member surrounding said jaw member and having fingers adapted to engage said spring biased disc upon engagement of said jaw members to move said disc axially to permit rotation of said jaw members.

2. For use in an engine starter having a housing, an assembly comprising an axially stationary rotatable spline nut, a screw shaft splined to said nut for rotation with and axial movement relative thereto, a starter jaw member secured to said screw shaft for rotation and axial movement therewith, a spring biased disc connected to said housing, spring means biasing said disc into engagement with said starter jaw member, and means responsive to axial movement of said starter jaw member to remove the bias from said disc to permit rotation of said starter jaw.
